WATER HEATER CONTROL

Henry Dreyfuss, South Pasadena, Calif., assignor to
Minneapolis-Honeywell Regulator Company, Minne-
apolis, Minn., a corporation of Delaware

Application November 8, 1955, Serial No. 38,798

Term of patent 14 years

(Cl. D78—1)

The drawing figure is a perspective view of a water heater control embodying my design.

The opposite side of the water heater control is substantially plain, there being only a threaded inlet hole therein for the reception of a gas supply pipe.

The back of the control is substantially plain, there being a conventional rod and tube temperature responsive element projecting rearwardly therefrom for insertion into a water heater.

I claim:

The ornamental design for a water heater control, substantially as shown and described.
